UNITED STATES PATENT OFFICE

LORING WASHBURN, OF GREENWICH, CONNECTICUT, ASSIGNOR TO S. H. POMEROY COMPANY, INC., OF NEW YORK, N. Y., A CORPORATION OF NEW YORK

AUTOMATIC CLOSING DEVICE FOR WINDOWS

Application filed October 2, 1929. Serial No. 396,824.

It is old in the art to provide means whereby the mass of the counterbalance weights of the lower sash shall be transferred to the counterbalance weights of the upper sash 5 so that when the lower sash is released from its counterbalance weights, as in the event of fire, not only will the lower sash drop from an open position to a fully closed position but the upper sash will be raised from 10 an open position to a fully closed position. Various devices intended to permit such a result to be accomplished have been proposed heretofore but have been so complicated in construction or so liable to derangement that they have not gone into general 15 use or have been of such a character as to render it impossible to let the meeting rails of the two sashes pass the top and bottom rails of the two sashes, respectively, after 20 the automatic closing devices have been installed so that the meeting rails can be properly and completely painted, whereby it has been impossible to complete the installation of the automatic closing devices when the 25 rest of the installation of the window is accomplished and it has been necessary to complete the installation of the automatic closing devices at a later time after the painting job has been completed, thus increasing 30 the cost of installation.

It is the object of the present invention to provide an automatic closing device which will permit the meeting rails of the two sashes to pass the top and bottom rails of 35 the two sashes, respectively, and the painting job to be completed after the closing devices have been installed. In accordance with the invention there is connected to each 40 of the counterbalance weights of the lower sash, a lost motion connector to engage at its other end the corresponding counterbalance weight of the upper sash and of such length as to allow, after its installation, sufficient relative movement of the two sashes 45 to permit the meeting rails to be exposed for painting. The invention will be more fully explained hereinafter in reference to the accompanying drawings in which it is illustrated, and in which:

50 Figure 1 is a view in sectional elevation

showing a portion of a window jamb with the counterbalance weights, chains and pulleys and the improved device through which the mass of the lower sash weight may be applied to the upper sash weight when the lower sash weight is released from the lower sash. 55

Figure 2 is a view similar to Figure 1 but showing the relations of the parts when the lower sash weight is about released, the 60 positions of the two sashes being those assumed after the lower sash weights have been released, the lower sash itself with its connection to the chain connection and the upper sash being indicated by broken lines. 65

Figure 3 is a view in section on the irregular plane indicated by the broken lines 3-3 of Figure 1, looking down.

The construction of each window jamb *a* and of the head *b* may be as usual or preferred, each jamb being adapted to receive within itself the upper sash weight *c* and the lower sash weight *d*, and to support the sash pulleys *e* and *f* over which pass the counterbalance chains *g* and *h* by which the sash 70 weights *c* and *d* are connected, respectively, with the upper sash *c*¹ and the lower sash *d*¹. Each chain *h* of the lower sash is shown as provided at some point where it will be exposed outside of the jamb when the lower 75 sash has been raised, with a fusible link of usual construction, shown as comprising two parts *i* and *i*¹ which are united by a ball *i*² held in place by easily fusible solder. To each lower sash weight *d*, as at *k*¹, is connected a lost motion connector *k*, preferably 80 a short length of chain, which has at its other end a device, such as a hook *k*², adapted for engagement with the upper sash weight *c*, preferably engaging directly the chain *g* of the upper sash weight. The connector *k* furnishes a means by which the lower sash weight *d* is connected to the upper sash weight *c* so that the mass of the lower sash weight shall be added to the mass 85 of the upper sash weight when the lower sash weight is released from the lower sash through the operation of the fusible link or in any other way. Not only is the connector 90 preferably flexible but, in order that the 95 connector

purposes of the invention may be realized, it is of such length as to provide for limited lost motion as between the upper and lower sash weights at each side, so that when the 5 window with its automatic closing device has been completely installed the lower sash can be raised with respect to the upper sash to permit the meeting rail of the lower sash to be exposed above the top rail of the 10 upper sash for painting when the upper sash has been lowered and similarly so that the upper sash can be lowered with respect to the raised lower sash to permit the meeting rail of the upper sash to be exposed for 15 painting.

While the foregoing description has related mainly to the sash weights and chains at one side of the window it will be understood that a similar connector is provided 20 at each side of the window. It will also be understood that the form of each connector employed may be varied to suit convenience provided it is of such a character as to permit limited lost motion as between the two 25 sashes sufficient to expose the meeting rails, as above described.

I claim as my invention:

1. In a window the combination of upper and lower sashes, upper and lower sash 30 weights, chains connecting the sash weights with the sashes, respectively, the chain of the lower sash being separable, and a lost motion connector connected to each lower sash weight adapted to so engage the cor 35 responding upper sash weight as to impose its weight thereon when the lower sash weight is released, said lost motion connector being adapted to permit the lower sash weight to drop substantially below the level 40 of the upper sash weight before causing the weight of the lower sash weight to be imposed upon said upper sash weight.

2. In a window the combination of upper and lower sashes, upper and lower sash 45 weights, chains connecting the sash weights with the sashes, respectively, the chain of the lower sash being separable, and a relatively slack and flexible connector connected to each lower sash weight adapted to so en 50 gage the corresponding upper sash weight as to impose its weight thereon when the lower sash weight is released, said slack and flexible connector being adapted to permit the lower sash weight to drop substantially 55 below the level of the upper sash weight before causing the weight of the lower sash weight to be imposed upon said upper sash weight.

This specification signed this 27th day of 60 September, A. D. 1929.

LORING WASHBURN.
